CENTRIFUGAL PUMP

Harry E. La Bour, Elkhart, Ind.

Application November 5, 1934, Serial No. 751,445

14 Claims. (Cl. 103—103)

The present invention relates to centrifugal pumps.

The chief object of the present invention is to provide a pump of high hydromechanical efficiency and simple rugged construction.

A further object is to provide a pump which will produce a desired pressure over a wide range of delivery, i. e., outflow from the pump.

A further object is to provide a novel method 10 of pumping whereby the desired pressure may be realized in a centrifugal pump over a wide range of delivery, i. e., outflow from the pump.

A further object is to control within the pump 15 itself the distribution of pressure and flow, whereby by flow restrictions in the intake and discharge passageways are eliminated and a great increase in volumetric and hydro-mechanical efficiency is attainable.

The specific embodiment herein shown is a 20 multi-throat pump employing an open impeller. With the specific form of pump herein disclosed, I have been able to realize high efficiencies even in small capacities, with accompanying advantages of compactness, simplicity and low cost.

25 In the accomplishment of the aforesaid chief object, I construct the casing, impeller and discharge passageways in such form and proportions as to secure the desired velocities which are to be generated and the flow to be carried with a 30 high degree of streamline flow.

It is to be observed that if approximate streamline flow through the pump is to be attained, each functional part of the pump which has to do with flow must be coordinated with the others so that 35 these elements, most of which operate in series with each other, will not interfere with attainment of efficiency of the whole.

The preferred form of pump which I shall herein describe and illustrate is an open impeller 40 pump. It is a familiar fact that an open impeller pump will generally not operate at as high mechanical efficiency as a closed impeller pump, other things being equal. Open impeller pumps have certain advantages such as simplicity, lower 45 cost, less tendency to clog up etc., and hence there is a real demand for a high efficiency low cost open impeller pump.

The chief reason for the lack of efficiency in 50 pumps of the open impeller type I conceive resides in the fact that the water is carried idly in frictional contact with the side walls of the pump casing. I have observed that the liquid to be pumped must be moved radially and angularly in order to attain the desired velocity. But after 55 it has traveled the required distance radially and

angularly to attain the desired velocity, I conceive that it should be promptly discharged. Now in order to produce the minimum travel angularly, the impeller must be coordinated in form, size and speed with the intake and discharge so that the liquid picks up its velocity in minimum angular travel and is then promptly discharged. This coordination of attainment of velocity and arrival at a point of discharge I term synchronism or synchronous operation. By coordinating synchronous operation with the proper shape of the passageways I am able to develop efficiencies and outputs never before attained in comparable sizes of impellers or pumps.

The present invention embodies a new principle 15 applicable to multiple throat centrifugal pump devices. That principle, as will be explained more fully below, comprises the simultaneous control of distribution of flow and the development of pressure at the multiple discharge throats by 20 internally regulating the ratio of angular travel to radial travel of the operating medium in the impeller in advance of release into the throats. According to the best application of this principle each and every particle of fluid is free to 25 flow into the pump, and is free to flow out of the pump without any flow restriction or any interruption except that each and every particle must in flowing through the pump pass through a 30 definite angular travel at the periphery of the 30 impeller.

There are at least four distinct features, which, according to the teachings of my pump, combine to produce the desired advantageous results in regard to efficiency, and output.

The first feature is the introduction of the water into the impeller. The second is the travel through the impeller. The third is the transition of the water from the impeller to and through the discharge throats; and fourth, the combining of 40 a plurality of streams into the common discharge.

According to the preferred form of the present invention the working fluid is free to flow into those parts of the impeller which are passing over the concentric portions, and in fact to every point 45 on the periphery of the impeller, the blades being of negligible width compared to the width of the ports. But while the fluid can flow freely into the impeller, it cannot flow radially outward of those parts of the impeller which at any instant are passing over the closed or concentric portions. Neither can it flow out of any part of the impeller without first passing over the concentric portions or sealoffs. Radial flow at the periphery is stopped by these concentric portions 50 55

or sealoffs, and radial pressure is developed as angular travel occurs.

The working fluid which is at any instant passing or about to pass over a concentric portion is temporarily held against radial flow while angular travel occurs. Then, having been given angular motion and hence having acquired a predetermined inertia of motion, the working fluid is allowed to escape from the periphery of the impeller and be thrown or impelled through a throat which is suitably proportioned to the other characteristics of the pump, so that maximum velocity of the working fluid occurs at this point.

These throats lead through relatively long expansion passageways where velocity is gradually transformed into pressure. These long expansion passageways all lead to the common discharge outlet in parallel and, as far as possible, at the same velocity and at a small angle to each other, so as to minimize all shock.

The greatest difficulty with multiple discharge pumps as heretofore known has been the problem of equalizing pressure and flow around the impeller, i. e., at the various branches or passageways where liquid is intended to be discharged. Unless provision is made to prevent it, one part of the impeller and one throat will provide most of the discharge, and the remainder of the impeller and the other passageways allow useless work to be done on the working fluid, with resultant loss of efficiency. The art heretofore has attempted to equalize the discharge, either by placing flow restrictions in the outlets, such as the so-called diffusers, or by placing constrictions in the inlets leading to the various parts of the impeller.

According to my invention, no restrictions are provided at either the inlet or in the discharge passageways. Both these passageways are preferably formed so as to provide maximum freedom to flow so that efficiency is not lowered. I secure control of distribution by the same means which insures adequate discharge, i. e., by the concentric portions of the channel which insure the acquisition of adequate discharge pressure. This concept of free entry into the impeller and free outward flow beyond the throats is, so far as I am able to determine, broadly new, and constitutes the introduction of a new principle into the art of moving fluid by centrifugal effect. The principle of my invention is independent of the working fluid. The invention is applicable not only to multiple discharge centrifugal pumps, but also to centrifugal blowers or fans operating on gases. The principle is also independent of the particular type of impeller. My invention is broadly new as applied to open impellers or closed impellers, and for either liquid pumps or gas blowers or fans.

60 The results secured by my invention are not only greater mechanical or hydraulic efficiency, but much greater output from a given size of impeller and casing, and a much wider range of deliveries at a given head.

65 The water must be twisted off the intake stream and begin its acceleration angularly and radially with minimum friction, shock and eddy currents, and my construction is highly efficient in securing this effect.

70 With respect to the phase of acceleration of the water in the impeller, my invention aims to bring the water smoothly and with minimum travel to maximum velocity and immediately thereupon remove the water from further engagement with the impeller. As soon as the

water has had imparted to it maximum energy, i. e., is brought up to full velocity, it is discharged from the working chamber. Any unnecessary travel particularly at maximum velocity results in friction losses and eddy current losses and detracts from both mechanical and volumetric efficiency. In the form of pump herein disclosed, three discharge throats are provided. This number may be varied, but the desideratum is to have the water discharged as soon as it has reached discharge pressure or velocity, and not be carried angularly any further than necessary. The preferred form of impeller blades of my invention are shown as substantially straight with the tip or end of the blade curved back only to the extent of avoiding the formation of eddy currents at the blade tips. I have employed absolutely straight blades with excellent efficiency but there appears to be a whistling noise that is undesirable. The straight blade brings the liquid to maximum velocity in the least angular travel and makes the least frictional contact with the water, and due to maximum acceleration of the liquid allows the use of more throats for the discharge.

25 In the three throat pump, the ideal action for maximum efficiency and capacity is to have full pressure developed within substantially 120 degrees of angular travel, and the more nearly this synchronism is accomplished, the better will 30 be the performance of the pump. This ideal may not always be attainable in production, but according to my preferred embodiment, it is closely approximated within the practical tolerances of commercial manufacture. I consider that the 35 production of the synchronous operation above described is broadly new.

40 The number of blades is an important consideration. Theoretically, the space between blades should be relatively small, and the blades should 45 occupy no space, but practical considerations require the blades to have sufficient body and strength to withstand mechanical service and corrosion. I have adopted eight blades with a three-throat pump as a satisfactory working 50 comprise. Too much surface or too great a number of blades is not desirable. The use of eight blades with three throats gives an excellent balance which makes it easy to keep the packing gland tight. In referring to balance I do not mean mechanical balance alone but both mechanical and hydraulic balance.

55 At the important zone where the water emerges from the impeller and enters the throat, it has maximum energy, and here its treatment is most important. The impeller of my invention leaves the water stream with minimum disturbance. I promote this by a slight rounding or curving back the tips or ends of the blades. The object here is to provide, as nearly as possible, a smooth stream line flow of the slip between the blade end and the outgoing stream. I am aware that blades with long trailing tips have been proposed for securing pressure increase, but the impeller of my invention is designed for no such purpose, as the long trailing tip intended to secure higher pressure must be designed, I believe, to set up eddy currents to realize such high pressure. My impeller has straight blades slightly modified.

60 After the water enters the throat, it is allowed, according to my invention, to travel through a relatively long slender expansion passageway. Therein, the reduction of velocity and transformation into pressure is gradually accomplished 65

with minimum opportunity to depart from streamline flow. The expansion passageways of the pump of my invention extend peripherally about the pump for a considerable angular distance, and as nearly on the same radius as possible to each other. The chief direction of expansion is lateral, i. e., axial of the shaft.

This insures that first a high velocity stream does not discharge into a low velocity stream 10 with consequent shock and friction losses, and, second, so that when two streams are brought into contact, that is at a very small angle at slow speed and with minimum differential in speed and direction.

15 I believe the coordination of the synchronous action of building up the velocity in a fraction of the circumferential travel with immediate discharge and streamline flow produced by proper proportioning of the cross sections of the 20 passageways through the pump is broadly new.

A second and highly important object of my invention is to improve the mechanical structure of pumps of this character. Among the features provided to accomplish this object are the following:

1. An improved form of supporting and aligning bracket for coupling the pump casing to a suitable support, and to align the packing gland of the impeller shaft and the bearings of a supporting and driving shaft.

2. An improved form of assembly clamp for coupling the front plate to the pump casing to allow, conveniently, of any desired adjustment of the inlet and outlet relative to each other.

3. An improved and simplified form of packing gland and follower which keeps the pump shaft tight and makes servicing of the gland unusually easy.

4. A novel form of combined mounting and 40 cooling hub for the casing and packing gland.

Other and incidental objects and improvements will be apparent from the following detailed description, the drawings, and the appended claims.

Now in order to acquaint those skilled in the 45 art with the manner of constructing and operating a device embodying my invention, I shall describe, in conjunction with the accompanying drawings, a specific embodiment of the same.

In the accompanying drawings, in which like 50 reference numerals indicate like parts, Figures 1 to 6, inclusive, are diagrams to explain the operation of the pump;

Figure 7 is a side elevational view, with parts 55 broken away, showing one specific pump of my invention with its drive shaft and mounting;

Figure 7a is a fragmentary section through the pin of the modified form of a gland follower arm;

Figure 8 is a transverse cross section taken on the line 8—8 of Figure 7;

60 Figure 9 is a front view, partly in section, of the pump with the cover or inlet plate removed;

Figure 10 is a section taken on the broken line 10—10 of Figure 9, looking in the direction of the arrows;

65 Figure 11 is a side elevational view of the impeller which is shown in front elevation in Figure 9; and

Figure 12 is a fragmentary section taken on the line 12—12 of Figure 11.

70 Referring to the diagrams of Figures 1 to 6, I have indicated in Figure 1 a passageway of typical venturi shape with the throat, or narrow part of the passageway at A, with a converging portion at B and a diverging portion at C. Assume that it were intended to create a flow of

fluid through the venturi, this could be accomplished by moving a vane V at an accelerated rate to take the positions D, D¹, D², D³, D⁴, this vane occupying substantially the full cross section at each place, with corresponding velocities of movement. At position D⁴ the vane is removed from the stream.

If the rotor of a pump should be constructed so as to secure the operation above described, with the position D⁴ corresponding to the extreme 10 periphery of greatest radial extent of the impeller, it is conceivable that minimum loss due to eddy currents, by providing the substantially streamlined flow with an acceleration of the liquid, might be secured.

If, in the usual single outlet pump, indicated in Fig. 2, this theory be applied, then in order to secure streamline flow with minimum idle carry of the liquid, the liquid should flow from the inlet E at the center to the tangential outlet F 20 as a spiral stream. The velocity of inlet flow at the inlet E should be a minimum, with maximum cross section, increasing velocity occurring through the convergent or nozzle portion of the path as indicated at B, until maximum velocity 25 is attained at A at the most constricted portion of the flow, where the flow of the central part of the stream substantially leaves the tips of the impeller blades such as G. From the most constricted portion or highest velocity of flow, the 30 liquid then should continue to flow with decreasing velocity through the expanding or divergent nozzle portion C leading to the discharge outlet F.

It will be seen, however, that if synchronism be thus attained, the rest of the periphery of 35 the pump and the impeller is either idle or must carry water idly around the interior periphery represented by the dotted line H. Assume that in the case illustrated in Figure 2, the blades G of the impeller have brought the liquid from the 40 intake E to the discharge port which lies between the points I and J, to the desired velocity within 120° of rotation, that is, by travel from point H to point I. It can be seen that the impeller and pump casing could, theoretically, be capable of 45 discharging three times the amount of liquid which the pump is actually handling, as per the diagram of Figure 2.

But another defect is now apparent in the pump if it be constructed in accordance with 50 standard practice, and that is that the desired progressive constriction in the cross section of the stream from intake to point of maximum velocity cannot be attained by circumferential constriction. Hence, synchronism which I herein 55 teach is not practically attainable in that manner. A further requirement which I teach is that the constriction of cross section to give true, or approximately true, venturi flow must be secured mainly in an axial direction, i. e., by progressively 60 thinning the stream axially more than it spreads out circumferentially to fill the sector, otherwise flow is choked more at the central part of the impeller than it is at the periphery, where its velocity should be a maximum.

In Figure 3 I have illustrated diagrammatically and idealized, for the sake of clearness, the impeller 1 and a development of the casing and passageways of the pump of my invention, this impeller having a multiplicity of blades mounted upon a shaft 2 which is preferably formed integral with the blades. The casing provides an inlet passageway E which opens into a pocket 3 in the impeller to facilitate the distribution of liquid from the passageway E about the entire 75

circumference of the impeller. The casing defines an impeller chamber which, in cross-section, is shown by the outlines of the impeller 1 in Figure 3, this impeller terminating at the most constricted part of the outlet, as indicated by the reference character A, where the blade tips terminate. Beyond the blade tips the casing provides the divergent passageways C-C. From this diagram it may be seen that the cross section of the 10 passageways through which the liquid flows from the intake pipe E to the discharge outlet is intended to follow the general scheme of the Venturi pipe shown in Figure 1, wherein the impeller blades accelerate the liquid from the larger cross 15 section to maximum velocity at the minimum cross section, and from thence the liquid in an expanding passageway loses velocity and increases in pressure.

An impeller such as 1 moving in an annular 20 chamber with a continuous peripheral outlet will not give the desired efficiency or characteristics, one of the reasons being that the impeller will impart rotary motion to the liquid beyond the blade tips, and it is necessary, therefore, to provide 25 vanes which serve first to limit the radial travel of liquid driven by the impeller to permit a delivery pressure to be built up, and, second, to stratify the flow so that each passageway or portion 30 of the discharge flow will be conducted in an orderly manner through an expanding channel. These channels, I conceive, must then discharge into a common outlet through a suitable junction, this junction being so arranged that the difference in mean velocity of any two adjacent 35 streams, and the mean difference in direction of flow of the streams, is a minimum. Since the liquid, in going from the inlet pipe E to the discharge, follows in general a spiral path, a number of discharge throats may roughly be determined 40 by determining the angular distance through which the water must travel in order to take up the desired energy from the impeller. Thus if, as indicated in Figure 2, the design speed and size of the impeller, the shape of the blades 45 and shape of the casing is such as to permit sufficient energy to be imparted to the water within 120° of travel, it will be obvious that a particle of liquid entering anywhere around the periphery of the intake pipe E should not be carried through 50 any appreciable idle travel if discharge ports were arranged at 120° apart on the periphery. Thereupon synchronism with a completely filled and active impeller will be attainable.

Multiple discharge pumps are known. It is 55 known by pump designers that a centrifugal multiple discharge pump involves the difficulty of controlling the distribution of work as between throats. If no provision is made to cure this there will be a tendency for one or more throats to 60 rob the others and produce an unbalanced condition which renders the pumping characteristics unsuitable for general use, and which interferes with volumetric and mechanical efficiency to an extent which largely destroys the value of the 65 design. I have conceived of the possibility of constructing a high efficiency multi-discharge port pump which, through the simple expedient of restricting radial flow of liquid in advance of each discharge port, will insure the functional 70 independence of the sections of the pump and compel each section to develop the desired delivery pressure, and hence do its own share of the work. Since this control resides at the point 75 where both radial flow and the development of pressure can be and are governed, the pump of

my invention requires no flow restrictions, inlet directors or outlet diffusers, such as have been employed in multi-throat pumps of the prior art. Also, my pump is thereby able to employ the streamline flow through Venturi-shaped passageways, as above described, without flow restrictions either on the inlet or outlet side. The result is that my pump operates, in a given size impeller, at superior efficiency.

In Figure 6 I have indicated how, in a three 10 throat pump, the desired synchronism may be attained. The throat spacing, as abscissal, is shown as 120°. The desired delivery velocity or pressure is indicated by the ordinates to be any desired value represented by 100%.

Taking into account the size (diameter) of the impeller; the shape thereof; the shaft speed desired; the delivery required, and the density of the liquid to be pumped, it is possible to build up the pressure within the angular distance allotted (120°) so that the liquid arrives at the throat as indicated by line OM at the exact instant of attaining its full delivery pressure. If the proportions be slightly different the delivery pressure may be developed before the liquid arrives at the 25 discharge port, as shown by line OL. Then the carry of liquid from L to M is idle or wasteful carry of water at high velocity.

If the proportions be changed, as by providing blades of greater curvature, the delivery pressure 30 will not be attained until the liquid has been carried through a greater angular distance than the minimum between throats as indicated by line OPN. In such a design the most efficient operation would be at a velocity or pressure corresponding to the height of point P above line OX. The pump could also deliver at higher pressure but at decreased efficiency, because of lack of synchronism. Were the blade formed so that full delivery pressure were not attained until the liquid 40 had been carried through 240° travel, as per line OSQ, then there would be two points at which the liquid could be discharged, as the first throat would tend to relieve the pressure at less pressure than is attainable at Q. Again the efficiency is 45 reduced because of lack of synchronism. The ideal condition of synchronous operation, together with proper shape of passageways for streamline flow and smooth acceleration and deceleration of the liquid, provides maximum efficiency, and it is 50 the object of the present pump to embody the same.

In Figure 7 I have illustrated, in side elevational view, a specific embodiment of my pump with a suitable support and mounting, and driving 55 mechanism therefor.

The pump 10 comprises three chief parts, namely, the impeller 1, the main body and casing 12, and the cover or inlet member 13. The impeller shaft 2 is coupled to a suitable driving 60 shaft section 14, the coupling being in endwise alignment, as will be later described. The driving shaft section 14 and the impeller shaft 2 are coupled by a key 15 which lies within telescoping splines formed in the respective parts, the impeller shaft having a reduced end or stud portion which fits within an axial recess 16 in the adjacent end of the driving shaft section 14, a threaded rod or bolt 17 extending through the hollow shaft section 14 and being threaded into the end 70 of the impeller shaft 2 and provided externally with a tightening nut 18 to pull the shaft section 14 and the impeller shaft 2 into telescopic relation and in alignment, this being particularly facilitated by the sliding fit and the provision of 75

the shoulder 19 at the junction of the stud or reduced portion of the impeller shaft with the full section thereof. This shoulder engages the end face of the driving shaft section 14.

5 The impeller shaft 2 is designed to be guided concentrically of the packing recess 20 which is formed about the shaft opening through the hub 21 formed on the main pump casing or frame 12. This hub 21 projects axially from the side wall 10 of the pump casing or frame, and is provided with a flat, annular machined surface 22 which provides a clamping surface against which there is bolted a similar annular surface on a cooperating clamping member 23, which is preferably 15 ring-shaped in form and provided with a cooperating clamping surface engaging the surface 22. The hub 21 is provided with an extending piloting flange 24 to facilitate the fastening of the hub member 21 and the clamping member 23, as 20 by a series of studs 25. Cap screws may be employed instead of studs. The clamping member 23 and the flange 24 are preferably piloted together by interengaging annular shoulders, as indicated at 26. A supporting pedestal 27 is 25 adapted to support both the driving shaft section 14, with its connected impeller shaft 2 and impeller 1, and also to hold the pump casing or frame in proper alignment. This pedestal member 27 includes the base portion 28, the clamping member 23, and the supporting arms 30-30 which support the pump by cantilever action. These arms 30-30 are relatively thin, vertically disposed plates which merge into the clamping plate or slotted ring-like member 23 that is 35 bolted against the flange 24 of the hub 21. These arms 30, at their opposite ends, are formed integral with the central part of the pedestal member 27, which central part includes the apertured or ring-like clamping members 31, 32 for supporting the bearing for the shaft section 14. The ring-like members 31, 32 are formed at their lower ends integral with the base portion 28, the base portion 28 being hollow.

The shaft section 14 is supported at the bearings 33 and 34, these bearings being shown as ball bearings having the inner rings mounted on the shaft section 14 as by means of a shoulder on the shaft section, a clamping ring 35 for the bearing 33, and a similar clamping ring 36 for the bearing 34. The outer rings are mounted in a cylindrical sleeve member or barrel 37 which has extending flange portions at 38, 39 for cooperating with the split rings 31 and 32. Cap members 40 and 42 are held by suitable bolts such as 43 and 55 44 against the corresponding ends of the barrel member 37 and hold the outer races in place. The outer race of the bearing 34 is held in place endwise to limit the axial travel of the shaft section 14 and hence of the impeller 1 in the pump casing 12. The outer race of the bearing 33 is merely confined circumferentially and is allowed to float in the axial directions.

The impeller shaft 2 carries a liquid slinger 45 which cooperates with the end cap 42 to prevent the travel of liquid along the shaft 2 into the bearings or into the junction between the two shaft sections. The barrel 37 may be provided with a suitable filling of oil or grease as through the plug 46, a drain plug 47 being provided at the rear.

It will be seen that the flanges of the barrel member are less in diameter than the opening through the slotted clamping ring 23 carried by 75 the arms 30-30. The barrel member and the

bearings thus may be removed without disturbing the main body of the pedestal member 27.

The base 28 is provided with flanges upon opposite sides such as indicated at 48, suitable feet such as 49-49 being formed on the four corners 5 for mounting the base 28 upon a suitable surface 50.

The barrel member 37 and ring 32 are piloted together by registering grooves or keyways into which a pin or key 52 may be disposed for accurate alignment and assembly of the parts.

While the ring members 31 and 32 are preferably split and then clamped upon the flanges 38 and 39, the parts may be provided merely with a suitable concentric fit and bolted in place by 15 overhanging flanges, if desired.

Within the axial packing recess 20 in the hub 21 I provide suitable packing material 20' which is compressed upon the shaft 2 by a suitable gland follower 53 which fits within the axial recess 20 and is guided therein to compress the packing material 20'. This gland follower 53 is provided at its outer end with a recess adapted to receive packing material 54 and a secondary gland follower 55 seals the outer end of the gland 25 follower 53 upon the shaft 2. The intermediate, or main gland follower 53 is provided with a circumferential recess with which there communicates a lubricating pipe 56 (see Figure 8) to the outer end of which a compression grease cup is 30 preferably connected. A follower ring 57 mounted on the shaft 2 is adapted to engage the end of the secondary gland follower 55 and apply a yielding pressure to the main gland follower 53 thereby to retain packing in the recess 20. 35

The secondary gland follower 55 may be split so as to be removable if desired. The ring 57 has a recess which embraces the end of the follower 55 and provides the necessary hoop strength for the outer end thereof, the inner end of the follower 55 being restrained in the recess in the outer end of the main gland follower 53.

The ring 57 has a pair of notches (see Fig. 8) into which are extended the short pins or studs 59-59 of a fork member 60 formed on the lower 45 or vertical arm 62 of a bell crank lever 63 which is pivoted upon a pin 64 extending loosely through the bell crank lever and through the plates 30-30 and held in place as by cotter pins 65-65 (see Fig. 8). The bell crank 63 may be 50 provided with an eccentric sleeve 120, held in place by a set screw 122 and being adjustable angularly by the hexagon head 123 to raise or lower the pivot about which the arm 62 swings.

The horizontal arm 66 of the bell crank lever 55 63 is provided with a fork 68 at its outer end, this fork 68 being adapted to receive the shank 69 of the eye-bolt 70 between the tines thereof. These tines 68 are notched transversely to receive the ends of the pivot bar 74 which, in effect, forms a 60 knife edge bearing in the aforesaid notches. The pivot bar 74 has a central hole through which passes the shank of the eye-bolt 70 and a compression spring 75 bears upon the said pivot bar 74 and is adjustably stressed by the wing nut 65 76. The eye-bolt 70 is supported on a transverse pin 72 which passes through the plates 30-30 and is held against endwise displacement by the cotter pins 65-65.

To service the packing gland, the wing nut 76 70 is released to allow the bar 74 to be raised out of the notch in the fork 68; whereupon the eye-bolt 70 may be swung about the shaft 72 to release the same from the horizontal arm 66 of the bell crank lever 63. If desired, the trans- 75

verse pin 72 may be removed, but this is not usually necessary. The lever 63, however, is preferably removed to provide access to the gland and follower. This is done by withdrawing one 5 of the cotter pins 65, pulling out the cross pin 64, unhooking the pins 59 from the notches in the ring 57, whereupon the bell crank lever 63 may be withdrawn, making the entire gland readily accessible from the space between the two 10 plates or arms 30-30. Since these plates 30-30 do not extend substantially below the center line of the packing gland and its shaft 2, the lower half of the gland is quite open at all times, and with the lever 63 out of the way a high degree of 15 accessibility is afforded. In Figures 7 and 8 it will be observed that the lower edge of the arms 30-30 lies above the top of the shaft 2.

If it is desired to remove the impeller 1 the pressure on the packing gland may be released 20 by throwing the eye-bolt 70 and its spring 76 and cross bar 74 out of register with the fork 68, whereupon the pressure upon the packing is released. The shaft section 14 may then be uncoupled from the shaft 2 by loosening the bolt 17 25 or the nut 18 and pulling the impeller 1, with its shaft 2, to the left as viewed in Figure 7. The liquid slinger 45 is relatively loose upon the shaft 2 and may readily be stripped off of the end of the same, and the shaft 2 thereupon pulled 30 through the packing gland and out of the open side of the pump frame or casing 12, the inlet plates 13 being removed.

If it is desired to remove the bearings, this may readily be done by releasing the barrel 37 from 35 the rings 31 and 32. Where it is desired to remove the barrel and the shaft section 14 with the pump, the studs or bolts 25 which hold the pump to the pedestal member 27 are loosened, the bell crank 63 is pulled out of the way, the barrel 37 is released from the rings 31 and 32, and thereupon 40 the shaft section 14 with the barrel may be pulled out through the clamping ring 23 which is large enough to permit these parts to pass. It will be observed that the clamping plate or ring 23 is preferably cut away at the bottom (see Figure 8). 45 This is done to facilitate assembly and also to prevent liquid of a corrosive character from attacking the clamping plate or ring. Obviously the ring 23 need not be so cut away.

The hub 21 is provided with an annular water 50 passageway surrounding the main packing for cooling the same. Water may be introduced into this cooling chamber or water jacket either from an external connection, such as the delivery side 55 of the pump, as through a pipe 17, the water then being discharged through a passageway 18 to the runner chamber near the hub thereof, or the circulation for the water jacket may be entirely 60 internal, by providing an inlet passageway to the water jacket from a point where the pressure is greater and a discharge at a point where the pressure is less, such points existing at different radial distances within the casing.

The hub and supporting construction which 65 I have shown may be varied. In fact, the pump casing 12 may be supplied with a solid hub 21, as shown in Figure 10, for mounting in a split clamp carried by the arms 30-30 instead of the clamping ring 23. Such form of hub and split 70 clamp is shown in my Patent No. 1,993,999, issued March 12, 1935. The gland and follower construction and the bearing construction are preferably of the form shown in Figure 7.

Referring now to Figures 9, 10 and 11, the cas- 75 ing or main pump frame comprises a substan-

tially flat wall 80 which has a junction with the hub 21 or 21', as the case may be, the said hub having a central opening for the impeller shaft 2 and an axial recess 20 about the same for the main packing. This end wall may be suitably reinforced by radial ribs or flanges, if desired. The end wall 80 has a finished interior surface 82 forming the side of the runner channel. The inner surface of the wall 80 is relieved from said machined surface 82 to the center. This obviously, is optional. This end wall 80 is substantially disc-shaped and its outer periphery merges into the volute portion and into the outlet connection or nozzle 84 in the following manner. The nozzle or outlet is provided with a clamping flange 85. The wall 86, which defines the adjacent part of the outlet, is joined to a circumferential wall 87 and the junction of these two walls forms a cut-off 88 defining the termination of one discharge port 89. The wall 87 is curved about the axis of the impeller shaft for a short distance as a cylinder then continues on an increasing radius and its inner surface defines for a short distance the cylindrical bottom of the runner channel then continues as a passageway communicating with the discharge port 89. The wall 87 continues in spiral form to form the outermost wall of the volute 83 and finally ends up at the flange 85. The end of the discharge port 89 is defined by a spiral wall 91, the forward end of 20 which 92 forms a cut-off for the discharge port 89. This wall 91 continues for a short distance as a cylinder then proceeds in spiral form, defining between itself and the outermost wall 87 a spiral passageway of gradually increasing cross 25 section, said wall 91 finally terminating at 93 substantially in a feather edge. On its inner side the wall 91 forms for a short distance the cylindrical bottom of the channel then continues as a passageway for the discharge port 84. The discharge 30 port 84 terminates at the edge 95 of another spirally disposed wall 96 which wall 96 forms, between its outer surface and the inner surface of the wall 91, a gradually expanding passageway 97 which merges beyond the feather edge 93 with 35 the discharge of the passageway 88. The wall 96 extends between the passageways 81 and 91 for a short way as a cylinder, then continues as a spiral wall and terminates in a feather edge at 40 98, so that the stream from the passageway 81 merges with the liquid from the passageways 88 and 97, which have previously merged.

Each of the three sections of the channel is thus provided with a cylindrical portion which is concentric with the impeller 1, and of a radius which except for mechanical clearance is substantially the same as that of the impeller. This cylindrical portion represents the angular carry of water to build up delivery pressure. The walls or vanes 91 and 96 are relatively thin platelike 55 portions with the trailing ends gradually tapered to approximate feather edges for leading the adjacent streams together smoothly. The thickness of the vanes is not the important feature, but the shape should be such as to form, in conjunction with the cooperating walls in each case, a gradually increasing passageway to provide a smooth deceleration and increase in pressure. Sharp changes in direction or velocity in the passageways are to be avoided.

It will be observed that the axial depth or width of the blades of the impeller 1 is relatively small as compared to the diameter of the outlet opening or nozzle 84. The outlet opening 84 is preferably circular, as is the flange 85. The 70

flare or progressive increase in cross section from the discharge ports to the outlet 84 of the respective passageways is secured chiefly by increasing their axial dimensions as they lead from the periphery of the impeller to the outlet opening 84.

Thus, by reference to the width of the passageway as indicated in Figure 10 it will be seen that the axial dimension or width of the channel run is shown by the position of the wall 80. The width of the passageway 97 is indicated by the position of the wall 100, and the width of the passageway 98 is indicated by the position 15 of the wall 101, all in Figure 10. Thus, by securing the flare, or increase in cross section mainly by increasing the axial dimension, the casing of the pump may be made more compact and of substantially less size in a radial direction.

It will be observed that in the embodiment illustrated in Figure 9, there are three discharge ports leading to the common outlet 84 substantially without constriction. Between the outlet ports 89, 90 and 94 there are concentric cylindrical portions or walls with which the tips of the blades have substantially only mechanical clearance. These cylindrical bottom portions of the channel in conjunction with the impeller 2 form radially restraining walls whereby each of the 20 three sections of the pump is at all times functionally substantially closed off from the other sections by the impeller blades whether these blades be parts of an open runner or of a closed runner. The blades are preferably spaced apart 25 a distance which is substantially not greater than the extent of the radially restraining portions, so that at least one blade is always in registering relation with respect to a substantially cylindrical wall of the bottom of the channel for each 30 of the three parts of the pump. These radially restraining portions to that extent act functionally as sealoffs. It is to be understood that the functional effect of predominating angular travel followed by the functional effect of predominating radial travel in proper synchronous relation 35 is the characteristic sought. Variations of form are not important so long as the above characteristic is predominant. Even if the blade tips have more than mechanical clearance, the effect 40 is not lost so long as the liquid which is carried on the cylindrical channel walls is responsive to the blades in partaking of angular carry to acquire discharge velocity or pressure in advance of release radially into the discharge ports.

The shape of the impeller blades is also capable of considerable variation, so long as the above characteristic synchronous action is maintained.

A draining opening 102 through the wall 91 and a draining opening with a plug 103 through 45 the wall 87 permit liquid to be drained from the pump to avoid injury by freezing.

The main pump casing or frame 12 is provided with a cylindrical recess which terminates at its end on the machine surface 82, this cylindrical recess being of such diameter as to permit the insertion of the impeller 1 from the left as viewed 50 in Fig. 7. This recess is machined out to provide a cylindrical surface at 104 (see Fig. 7). A short flanged neck 105 is formed on the left-hand end 55 wall as viewed in Figures 7 and 10 for the connection of the cover or inlet member 13. This inlet member comprises an annular flat wall section 106 with a machined surface parallel to the machined surface 82 to form the front side of 60 the runner channel. A cylindrical wall portion

or cylindrical flange 107 fits within the bore 104, and a radial flange 108 extends out beyond the flange neck 105, a suitable packing gasket being interposed between the flange 108 and the neck 105. A split clamping ring 109, having its inwardly extending flange adapted to be disposed back of the flange on the neck 105 registers with the outer periphery of the flange 108 so that studs or bolts 110 may clamp the split flange 109 and the flange 108 together. The split flange 109 is preferably split at two or more points, so that the parts thereof may be readily disposed in position to hold the parts removably together. The inner radial margin of the annular plate 106 merges into the converging conical wall 112 and this wall 112 in turn merges with the diverging wall 113, the junction of the two walls 112 and 113 forming the maximum constriction of the inlet passageway. The outer part of the wall 113 is provided with a suitable clamping flange 114 for connection to a corresponding flange on the inlet pipe.

The impeller 1, which is shown in dotted lines in Fig. 7 and in full lines in Figures 9 and 11, is formed in two somewhat dissimilar parts, but 25 these parts are so formed mainly for convenience in manufacture rather than for difference in operation. That is to say, considering the outline of the impeller 1 as viewed from the side (see Figures 7 and 11) this outline is the result of practical consideration rather than theoretical considerations. Theoretically considered, the impeller might better be shaped according to the strict converging Venturi shape shown at the point B in Figure 3, but for practical reasons the impeller is divided into two parts, namely, the extending blade ends 116, the axial faces of which lie in parallel planes for convenience in manufacture, and the wing portions 117 which take the form of truncated conical portions. In brief, the impeller of Figure 11 is the practical embodiment of the theoretical shape shown in Figure 3. The arms 116 are substantially oblong in cross section except for the reinforcing ribs 118 upon the backs thereof, and at the edge facing the intake the wings 117 are cut away at the center to provide an axial inlet recess which may be clearly seen in dotted lines in Figure 7.

The wings 117 are made as thin as possible in order to avoid occupying space which, at the central part, is difficult to gain except by increasing the axial length. It will be observed that the axial length or depth of the impeller at the central part is relatively great and that the corresponding shape of the runner chamber is made accordingly. In other words, the conical wall 112 follows quite closely, with clearance only, the taper of the wings 117.

The present pump is designed to impart to the liquid operated upon the necessary energy for 60 delivery pressures within approximately 120° of angular movement of the liquid. There is always some slip of the water or liquid with respect to the impeller, but obviously, efficiency is promoted by reducing such slip. In the present construction I have three discharge ports about the internal periphery of the runner channel and the open impeller has eight blades or arms tapering in axial depth from a maximum at the center, or adjacent the center, to a minimum at the tips. 65 The impeller is thus balanced mechanically and also hydraulically because the eight arms do not permit simultaneous register with the three ports. It will be observed that the blade tips 116 are given a backward curve. This is done mainly to 70 75

5 avoid noises and eddy currents at the point where the blade leaves the departing water at high velocity. If the blades could leave the water without slip, curvature on the ends of the blades 10 would be substantially ineffectual and all that would be required would be to give the blades a smooth, tapered end for withdrawing the same out of the current of water. As a practical matter, the blade ends must have sufficient substance 15 or material mass to provide the necessary strength to sustain the stress of driving the liquid, and to sustain some degree of corrosion.

10 The axial recess indicated at 3 in Figure 3 allows the water to enter the impeller without substantial constriction. Constriction at this point would mean that the velocity of the liquid would be unduly high, and this is undesirable.

15 The double taper of the inlet member provides a control which cuts down losses in the intake 20 through excessive rotation or helical travel of the water in the intake pipe. At the point where the water takes up angular motion instead of longitudinal motion there is a rapid change in direction and velocity. The throat at the inlet, as 25 indicated, tends to limit the formation of uncontrolled flow and eddy currents at this point, which is conducive to an increase in efficiency of the device. The form of pump herein shown carries out the thought of Venturi-shaped passageways 30 and streamlined flow to a high degree, even though the parts are not strictly in conformity to theoretical curves as indicated in Figures 1 and 3.

35 Figure 4 indicates diagrammatically the included blocks of water K lying between two adjacent vanes or arms of the impeller, and C indicates the divergent discharge passageway leading from the port which lies on the interior periphery H of the casing, this port being defined by the opening between points I and J. However, 40 the actual flow of water is not radial, but spiral, as indicated in Figure 5. The passageway comprises the spiral convergent portion B leading to the point of greatest restriction at A and discharging therethrough through the divergent discharge passageway C. In other words, the flow 45 of water, according to the diagram 5, is a transient phenomena occurring within the pump, the ratios of cross section at any point in the diagram of flow shown in Figure 5 being such as to allow the water to enter the impeller at a relatively low rate 50 of flow and then gradually to be accelerated until the narrowest part of the passageway is reached, at which point the impeller withdraws from action.

55 In the diagrams no attempt is made to show the actual dimensions or actual proportions, but merely to indicate the character thereof.

Figure 6 indicates the action of three streams of liquid according to the diagram of Figure 5. 60 Assume that the entire peripheral distance is indicated by the line O—X and the radial extent of the impeller by the vertical line O—Y. The distance O—X represents 360° and, for a pump of three discharge throats, the velocity of the water is increased from the center to the periphery through a certain angular carry, in this case approximately 120°, as above discussed.

65 Whereas I indicate 120° as the optimum, it is to be understood that the angular travel of the water may be greater than 120° for a three-throat pump, but it will be seen that if the travel be greater in angular extent than is necessary to have the desired energy imparted thereto, such excess travel introduces unnecessary 70 friction losses and reduces the volumetric effi-

ciency of the pump. As a pocket between blades is rotated from one discharge throat to the next discharge throat, the pocket is kept substantially closed at its outer end, so that liquid cannot escape freely until it comes into register 5 with the next pocket. Now at the same time, it is to be understood that the rate of movement of the pocket, while thus closed and carried between throats, is such that the desired discharge pressure (or centrifugal force) is developed. 10 The attainment of the desired pressure (or centrifugal force) and the arrival at the discharge position or port must concur to secure the desired synchronization. The diagram of Figure 6 is intended to convey the above thought. The physical structure which secures it is shown in Figure 9. The cylindrical bottom part of the channel between the point of cutoff 92 and the next port 94 illustrates the feature of functionally closing off the pocket between adjacent blades. The water contained in that pocket at the instant illustrated in Figure 9 (assuming the impeller to be rotating) is being moved angularly substantially without radial travel. It is thereby acquiring kinetic energy and developing centrifugal force. 20 Then when the pocket opens to the discharge passageway 94, the water from the pocket is released smoothly at high angular velocity, i. e., with maximum possible discharge pressure.

25 Release of the water in a pocket results in increase in the radial flow as compared to the angular travel. This means that the water is being delivered radially through the pocket with less work done upon it by the impeller. This is illustrated by the pocket in Figure 9 containing the 30 reference numerals 91 and 94. This produces an inertia of radial flow which assists in providing discharge. However, such radial flow begins to diminish as the pocket passes over the next cutoff as at 95. Then the water in the 40 pocket passing over the cylindrical portion following cutoff 95 substantially loses radial flow and takes up angular motion to develop kinetic energy (centrifugal force).

45 It will be observed that the sole obstruction to flow from the intake 13 through the impeller to the outlet 84 is that introduced by the cylindrical bottom parts of the channel. No inlet restriction for equalizing flow into the impeller, or outlet flow restriction or diffuser for equalizing 50 discharge as between discharge throats, is necessary. This principle of compelling the water to pass through a definite angular path, substantially without radial flow, as a means for securing distribution of work and a desired delivery pressure over a wide range of fluid deliveries, 55 is broadly new.

I am aware that it has heretofore been proposed to provide a centrifugal pump with multiple outlets, and I do not claim my invention so broadly as to include merely multiple outlets. 60 No one, so far as I am aware, has provided in a multiple outlet centrifugal pump definite portions of the channel in which the water is functionally confined radially for the purpose of acquiring centrifugal force in advance of release into the succeeding discharge ports. Such radial confinement and development of discharge pressure forms the sole means for controlling distribution of flow through the pump. I believe 65 it is broadly new to secure synchronous operation of a pump as above described. It is also broadly new I believe to coordinate the synchronous operation with the streamline flow secured by varying the cross section of the passageways 70 75

to approximate Venturi shaped conduits of flow.

Also I am aware that it has been proposed to employ impellers with long trailing tips to co-operate with specially shaped multiple throats with the object of attaining high discharge pressures, but my pump is not concerned with that structure or mode of operation.

Tests of the present pump in comparison with single outlet pumps, employing as nearly as possible the same shape of impeller, show conclusively the improvement in efficiency and head which may be obtained through the use of the present invention. A sample pump embodying the present invention equipped with 9 $\frac{3}{8}$ " diameter impeller, 1" in width, was able to deliver substantially the same volume and head as a comparative pump of the type which I have marketed under the designation #25-DW, having an outlet located at only one point on the periphery, and provided with a 10 $\frac{1}{2}$ " diameter impeller 1" in width.

The pump of the present invention designated as #30-QW in comparison with the considerably larger #25-DW showed markedly superior efficiency. The following is a comparative table of results:

1750 R. P. M.

30	G. P. M.	1 inch wide 9 $\frac{3}{8}$ inches diameter #30-QW		1 inch wide 10 $\frac{1}{2}$ inches diameter #25-DW	
		Hd.	Eff.	Hd.	Eff.
35	400	92	70	90	54.4
	350	96	69	95	55.6
	300	100	69	102	56.6
	250	104	66	106	54.3

I do not intend to be limited to the details specifically illustrated and described, particularly since certain of the details are engineering compromises to attain, as nearly as practically possible in workable form, certain optimum or theoretical constructions, the underlying principles of which I have above set forth.

I claim:

1. In a centrifugal pumping device, a casing provided with an axial inlet connection and a peripheral outlet connection, a runner chamber between said connections having unobstructed communication with said inlet connection, said chamber comprising a relatively narrow channel on the inner periphery of the chamber having a series of substantially tangential discharge ports substantially equally spaced about the periphery of the channel, there being substantially concentric arcuate bottom wall portions for the channel between discharge ports, the runner chamber having a relatively great depth axially at the inlet connection tapering in depth toward the channel and merging therewith to produce a passageway for liquid flow which passageway is convergent in cross section toward the discharge ports, said discharge ports having independent passageways leading in parallel to each other to the outlet connection, said passageways being separated by spirally disposed walls, said walls terminating in relatively thin edges to lead adjacent streams together with minimum shock, said passageways increasing in cross section from the discharge ports to the outlet connection and being free of flow restrictions, said runner chamber and said discharge passageways providing in effect a plurality of separate Venturi-like flow paths extending in parallel relation

from the inlet connection to the outlet connection, and a runner in said chamber, said runner having a plurality of vanes substantially greater in number than the number of discharge ports substantially to equalize the effect of the vanes upon the fluid flow through the ports, said runner having an inlet recess registering with the inlet connection to provide for relatively free entry of liquid into the impeller and to prevent undue inlet velocity.

2. In a centrifugal pumping device, a casing provided with an axial tubular inlet connection and a substantially tangential tubular outlet connection, said casing providing a runner chamber freely communicating with both said connections, said chamber comprising a relatively narrow runner channel on the inner periphery thereof, said channel having a plurality of substantially tangential discharge ports disposed substantially equidistant about the periphery, there being substantially concentric arcuate bottom wall portions for the channel between discharge ports, said chamber having a relatively great depth axially at the central part and tapering in cross section to merge with the runner channel and the outlet ports to provide in effect a converging passageway leading to each of the discharge ports, said discharge ports having relatively long spirally arranged overlapping discharge passageways free of flow restrictions and having a junction in the tubular discharge connection, said passageways being separated by relatively thin walls one of which terminates within the outlet connection said passageways progressively increasing in cross section from the port to the said junction, said increase being provided mainly by increase in the axial dimension of the cross section, said runner chamber and discharge passageways defining a plurality of Venturi-like flow paths extending in parallel from the inlet to the outlet, and an open runner in said chamber, said runner having a plurality of vanes substantially greater in number than the number of ports substantially to equalize the effect of said vanes upon the fluid flow through the ports, said runner having a depth of the vanes axially corresponding to the dimensions of the runner chamber, and having an axial recess registering with the inlet connection to provide relatively free entry of liquid into the runner and to limit the inlet velocity.

3. In a pump of the class described, a casing comprising two chief parts, said parts consisting of a body portion and an inlet portion, the body portion comprising a back wall, a series of integral spiral walls and end walls defining outwardly tapering discharge passageways between them, a tubular outlet connection forming a common junction for the outer ends of said passageways, and said casing having a cylindrical recess which terminates on the inside of said back wall, the margin of said recess having a short coupling neck, said inside back wall having an annular smooth surface forming the side of a runner channel, said inlet portion comprising a cover plate having a cylindrical portion fitting within the cylindrical walls of the recess and having an overhanging flange for attachment to said coupling neck, an axially disposed inlet connection providing an inlet opening for said cover plate, said cover plate having an annular smooth surface registering with said first annular smooth surface and forming the front side of the runner channel, said cover plate having a conical tubular portion leading from said runner channel to said inlet opening, said tapering discharge passage-

- ways terminating at their inner ends in a plurality of substantially tangential discharge ports and a substantially concentric peripheral wall in advance of each port forming a continuation of 5 the cylindrical wall of said recess.
4. A centrifugal pump comprising a casing having an inlet, a runner chamber provided with a runner channel and a plurality of discharge throats and an outlet, and an open runner in 10 said chamber with blades having their tips extending into said channel, substantially concentric walls between throats forming radial boundaries for water in parts of the impeller, said casing and runner providing a plurality of Venturi-shaped passageways between said inlet and outlet, with the blade tips and throats disposed at substantially the point of maximum constriction in 15 said passageways, said runner having blades of relatively little curvature and being adapted to be 20 operated at a rotative speed which will carry the water over said substantially concentric walls synchronously to discharge velocity and in register with each one of the throats.
5. In a centrifugal pump, a casing comprising 25 an impeller channel, said casing having an axial inlet and a peripheral discharge connection, a series of tapered passageways leading without flow restriction from the common outlet connection to ports opening into the channel, an impeller in the 30 casing running in the channel, functionally effective sealoff portions in the bottom of the channel between adjacent ports over which sealoff portions full discharge pressure is developed, said impeller having blades extending from the central 35 part of the casing to the bottom of the channel, the angular spacing between blades being not substantially greater than the angular extent of the sealoff portions of the channel, whereby each section of the pump is functionally sealed off at 40 all times from adjacent sections by interposed blades of the impeller, the blades being relatively thin at their tips to avoid obstructing the ports, the blades being greater in number than the ports and the inlet connection opening without flow 45 restriction into the central part of the impeller.
6. In a centrifugal pumping device, a casing having an impeller channel comprising peripheral substantially concentric walls at the bottom thereof, discharge ports opening through said 50 substantially concentric walls at a plurality of substantially equidistant points, a volute having a common discharge outlet, relatively thin vane-like walls providing tapered discharge passageways terminating in the volute, an impeller having 55 blades running in said channel, the ends of the blades being of small angular extent having substantially only mechanical clearance with the concentric portions of the bottom of the channel, said substantially concentric portions being of an 60 angular extent at least as great as the angular distance between the ends of adjacent blades of the impeller, said concentric portions, in cooperation with the rotating impeller, insuring delivery pressure at each of the ports and controlling the 65 distribution of flow of fluid between the respective ports and forming the sole flow restriction through the pumping device.
7. In a centrifugal pumping device, the combination of a casing having an axial inlet and a 70 discharge manifold leading to a common outlet connection, an impeller chamber within said casing, said impeller chamber comprising a channel, the bottom of which channel has angularly spaced substantially concentric wall portions 75 with discharge ports therebetween, said discharge 76
- ports being connected through unobstructed expansion passageways of outwardly tapering form leading in parallel to each other to the manifold, an impeller in said impeller chamber having blades the tips of which have substantially only 5 mechanical clearance with the said substantially concentric portions of the channel, the blades of the impeller being spaced apart angularly by a distance substantially not greater than the distance subtended by said substantially concentric 10 walls, whereby the sections of the pump between adjacent concentric portions are peripherally functionally closed off from each other at all times by the impeller blades the concentric portions in cooperation with the rotating impeller 15 constituting independent parallel pumping sections which at their inlets communicate freely with each other and with the axial inlet at the central part of the impeller, and communicate freely with each other on the discharge side of 20 the manifold beyond the expansion passageways.
8. A fluid moving device operating on the centrifugal principle, comprising a rotatable impeller having vanes and a casing enclosing the same, said casing providing a central inlet for fluid 25 permitting free and unobstructed access of the fluid to the central part of the impeller from which the fluid can flow outward to the periphery of the impeller, the casing comprising multiple throats leading to a common discharge through 30 expanding passageways which are free of flow restrictions and which direct the fluid streams in parallel at small difference in direction or velocity relative to each other, said casing having sealoff portions functionally closing off the periphery of the impeller registering with the same 35 to cause the fluid to be impelled with a high ratio of angular travel to radial travel whereby adequate delivery pressure is insured in the fluid when it arrives in register with the throats. 40
9. A fluid moving device operating on the centrifugal principle, comprising a rotatable impeller having multiple vanes the inner parts of which are substantially radial and the outer ends of which are curved back, the central part of the 45 impeller providing a chamber opening freely into the space between vanes in the impeller, and a casing enclosing the impeller, said casing providing a central inlet freely opening into said chamber in the impeller, said casing comprising multiple throats leading to a common discharge 50 through expanding passageways, which passageways are free of flow restrictions and which reduce the velocity of the fluid streams and bring them together all in the same direction relative to each other and at relatively small differences in pressure and velocity, said casing providing concentric portions functionally closing off the periphery of the impeller overlying the same for short distances in advance of the respective 55 throats to cause the fluid to be impelled with a motion which comprises a high ratio of angular to radial travel in advance of reaching the discharge throats, whereby adequate delivery of pressure and flow is insured at each throat. 60
10. In a centrifugal pumping device, a casing comprising an open central inlet and a runner channel defined laterally by side walls and defined peripherally in part by relatively thin vanes of approximately uniform thickness and of generally spiral form, between which vanes are formed outwardly tapered discharge passageways, adjacent passageways being arranged to discharge substantially in parallelism with each 65 70 75 76

other to join smoothly into a common discharge stream.

11. In a centrifugal pumping device, a casing comprising a runner channel defined by side walls and defined peripherally by relatively thin platelike vanes, the inner ends of the vanes being concentric to define the bottom of the channel and the outer ends of the vanes extending spirally to define between them spiral passageways of increasing cross section to permit gradual reduction of velocity of fluid discharged therethrough, adjacent passageways being arranged to discharge substantially in parallelism with each other to join smoothly into a common stream.

15 12. In a centrifugal pumping device, the combination of an open multibladed impeller comprising relatively thin radially extending arms, a casing comprising a runner channel for receiving the blades of the impeller, the casing having side walls defining the sides of the channel and having thin platelike vanes, the inner ends of said vanes being concentric with the impeller for an angular distance not substantially less than the angular distance between impeller arms, the 20 outer ends of said vanes extending spirally about

the axis of the impeller, the opposite surfaces of said vanes leading toward each other at the end at a small effective angle to bring the streams of fluid on opposite sides of a vane smoothly together.

5 13. The combination of claim 12 wherein the casing has an axial inlet freely opening into the central part of the impeller and a volute terminating in generally tangentially disposed discharge neck, one of said vanes terminating within 10 said volute and one of said vanes terminating within said neck.

14. In a pumping device, a runner and a casing comprising a single continuous inlet for fluid into the runner, a runner channel and a volute 15 surrounding the channel, said channel having a pair of adjacent discharge throats and expanding passageways separated by a thin vane the inner end of which is substantially concentric for a short angular distance to define the bottom of 20 the channel between throats, and the outer end of which vane is spirally disposed in the volute and terminates therein.

HARRY E. LABOUR. 25
